UNITED STATES PATENT OFFICE.

VINCENT A. TAYLOR, OF BEDFORD, OHIO.

DESIGN FOR A SEAT.

SPECIFICATION forming part of Design No. 22,396, dated May 2, 1893.

Application filed February 11, 1893. Serial No. 461,985. Term of patent 7 years.

To all whom it may concern:

Be it known that I, VINCENT A. TAYLOR, a citizen of the United States, residing at Bedford, in the county of Cuyahoga and State of Ohio, have invented and introduced a new and original Design for Pressed Leather Seats, of which the following is a specification, reference being had to the accompanying drawings, forming a part thereof.

Figure 1 is a top plan of a seat showing my design. Fig. 2 is a section on line 2—2, Fig. 1. Figs. 3 and 4 are sections on line 3—3, and 4—4, respectively, Fig. 1.

The leading features of my design consist in the shape of the seat, the outline whereof is that of a figure having four sides, rounded as at *a*, where adjacent sides join each other, with the seat pressed in such shape that a depression *b* is formed, the outline whereof corresponds or approximately corresponds with the outline of the seat, with the depression declining rearwardly from the front side of the seat as shown very clearly in Fig. 2, and with the depression rounded, as at *b'*, at the

junction of the rear and side-walls with the bottom of the depression.

Inside of each of the corners *a* of the seat, the surface of the seat is provided, with ornamentation *c*, and more especially with ornamental figures, such as scrolls *d* or wreaths *e* tied together, as at *g*, or both scrolls and wreaths tied together as shown at the front side of the seat in Fig. 1.

A seat embodying the design indicated presents a very beautiful appearance, and I would here remark that the ornamentation is located, as shown, entirely in the depression of the seat.

What I claim is—

The design for a seat herein shown and described, substantially as set forth.

In testimony whereof I sign this specification, in the presence of two witnesses, this 28th day of January, 1893.

VINCENT A. TAYLOR.
